SILENCER WITH TOROIDAL EXPANSION CHAMBERS

J. Ford Johnston, Hampton, Va., assignor of one-half to John R. Anthony, Jr., Takoma Park, Md.

Application March 31, 1949, Serial No. 84,573

5 Claims. (Cl. 181—57)

1

This invention relates to a silencer or muffler for suppressing the noise caused by the sudden exit of gas from or entrance of gas into a reciprocating pump, compressor, engine or other device which may transmit or otherwise handle gas with periodic pulsations.

Mufflers of conventional design employ chambers equipped with baffles, slots, holes, and like devices for creating turbulence in the flow of gas, all of which convert the kinetic energy of the gas into heat energy which results in an increased back pressure at the exhaust valve or a decreased induction pressure at the inlet valve.

The primary object of this invention is to suppress the noise attendant upon pulsating flow of gas by providing suitable chambers for transforming the pulsations into relatively continuous flow without converting kinetic energy into heat energy. This may be achieved by the application of commonly known aerodynamic and acoustic principles relating to the handling of flowing gases.

The secondary object is to produce such a muffler having physical characteristics which render it readily adaptable to low-cost, high-volume production, and which will be comparatively much smaller in size than mufflers of known construction for a given noise suppression and a given back pressure.

With these and other objects in view, the basic and essential principles of the present invention, as applied to an exhaust muffler, includes introducing the gas into a substantially round central expansion chamber, passing it into a peripheral, substantially annular or spiral shaped collection chamber through a communicating passage so designed as to impede the transmission of sound waves and minimize the transmission of pulsations in velocity and pressure from the one chamber to the other, the peripheral chamber being so shaped as to maintain a smooth flow of gas. It is a well-known principle of acoustics that a sudden reduction of area in a gas conductor will materially reduce the intensity of noise transmitted along the conductor, but past designs using this principle have always failed to maintain the kinetic energy of the gas, so that a high pressure differential was required to maintain the gas flow.

The velocity of exhaust gas leaving a valve port at beginning of exhaust is supersonic. The function of a muffler is to suppress the noise of the supersonic wave front by reducing its velocity as much as possible. In the silencer of the present invention, the gas expands as it leaves the inlet

2

pipe, and the expansion causes the conversion of pressure energy into velocity energy with the gas rotating at a high velocity around the inlet. This rotation causes a partial vacuum at the center of rotation, due to centrifugal force. The creation of the partial vacuum occurs after the supersonic wave has passed, and is maintained during the remainder of the exhaust stroke. Therefore, since the exhaust stroke is completed during a time when the pressure is low, the weight of exhaust gas remaining in the cylinder from one cycle to the next is minimized. In essence, the energy of the initial supersonic blast is utilized to provide a low pressure chamber into which the scavenging operation can discharge during the end of the stroke, which is the most important part of the stroke.

It will be obvious, of course, that the same design is effective as an intake silencer.

20 The invention is illustrated in the form of a two-piece casting, with parts riveted together. Using all the above-mentioned principles, the silencer takes in the gas at its center, lets the gas escape into the central expansion chamber 15 through diffuser vanes which impart to the gas a whirling motion about the axis of the inlet pipe, and then permits the gas to escape into a peripheral collection chamber through a peripheral slot. While the pressure waves causing objectionable noise will spread to the walls of the central chamber, only a small portion of them will escape through the slot into the peripheral collection chamber. The collection chamber preferably is 25 designed so that its cross section area at any point is proportional to the position of the point between the beginning and end of the peripheral slot, in order to achieve the maximum smoothness of flow.

20 The small part of the pressure wave which escapes from the central expansion chamber through the peripheral slot will enter all parts of the peripheral collection chamber at approximately the same time. Therefore, the wave front will not be concentrated at one point in the collection chamber, and its exit will be spread over the time required for sound to travel the circumferential length of the collection chamber. Most of the energy of the pressure waves will be absorbed by the walls of the two chambers as they

45 are reflected from side to side.

40 The pulsations in pressure of the incoming gas are smoothed out by the fact that the gas in any given pulsation enters the central chamber without striking against any baffle, but makes a gentle transitional curve in changing its direction, so

that a new pulsation meets no resistance except the gas in the central chamber, which is already whirling rapidly in the same direction as the new pulsation.

It has been found through experimentation that the peripheral slot area, for best performance, will generally be approximately one-twentieth to one-thirtieth of a square inch per brake horsepower of the engine.

The invention as illustrated in the drawings takes the form of a muffler and is shown, generally, in a two-part casting.

In the drawings, Figure 1 is a top plan view of the assembled muffler;

Figure 2 is a sectional view taken on the line 2—2 of Figure 3;

Figure 3 is a side view of the assembled muffler wherein certain portions of the inner construction are illustrated in dotted lines; while

Figure 4 is a sectional view taken on the line 4—4 of Figure 1.

The upper casting is indicated generally by reference numeral A, while the lower casting is indicated generally by reference numeral B. The upper casting A is provided with an annular extension 10 having a screw-threaded bore 11 formed therein, for attachment to the manifold pipe of an internal combustion engine or the like, wherein the pulsating gases to be muffled originate. The upper casting A is in the general form of a hemisphere, as indicated by reference numeral 12, while the outer periphery of the sphere is generally arcuately shaped, as indicated at 13, and an annular flange 14 is provided for attachment through suitable bolts 15 to the lower casting B. A substantially annular pipe 16 is formed integrally with the casting A, the pipe 16 having a plurality of angularly positioned diffuser vanes 17 formed therein.

The lower casting B, as illustrated particularly in Figures 2 and 4, is formed in substantially the shape of a hemisphere 20 and has a generally arcuately shaped outer periphery 21 with a flange 22 formed thereabout, the flange 22 cooperating with the flange 14 of the casting A, and bolts 15 extending through the two flanges to secure the two castings together. An annular pipe 24 extends upwardly from the bottom of casting B, the pipe 24 being so positioned to register with pipe 16 so as to form a continuation thereof, pipes 16 and 24 being positioned substantially centrally of the castings A and B. Pipe 24 is also provided with a plurality of angularly positioned diffuser vanes 25 so as to form a continuous slot with the vanes 17 formed in pipe 16. When the two castings are assembled through their flanges 14 and 22, as shown particularly in Figs. 3 and 4, the hemispheres 12 and 20 form a substantially spherical inner chamber 30. While this chamber 30 has been generally indicated as being spherical, it will, of course, be understood that it need not necessarily take the same shape as a sphere, although the same should be substantially toroidal. The arcuate extensions 13 and 21 form a substantially annular collection chamber 32, when viewed in cross section, the collection chamber 32 taking the form of a spiral, as indicated in the drawings, the area of chamber 32 gradually increasing from the point indicated at X as zero to the outlet opening 33.

The castings A and B are so shaped, at a point intermediate the expansion and collection chambers, as to provide a peripheral restricted slot 35 when the castings are positioned together, as seen particularly in Fig. 4 in order to act upon the

gases passing therethrough in a manner similar to a venturi. As the castings are subjected to certain heat and pressure, it is possible that the same may in time warp and, accordingly, suitable spacer elements 36 are positioned about the peripheral slot 35 so as to prevent the castings from closing which would in turn close the Venturi slot.

The bottom central portion of casting B is provided with a cone-shaped indentation 40 for purposes later to be described.

In operation, the assembled unit as illustrated in Figs. 3 and 4 is secured at the opening 11 to the source of pulsating gases. The gases enter the pipes 16 and 24 and through the aid of the cone 40 and angularly positioned diffuser vanes 17 and 25 pass into the expansion chamber 30 in a whirling motion. The gases will continue their whirling motion and hence be thrown outwardly within the expansion chamber 30 and pass through the peripheral slot 35 into the collection chamber 32 which, as has been noted, is generally in the shape of a spiral and gradually spreads from zero, as indicated at point X, to full area at the outlet port 33.

As before indicated, the incoming pulsating gases expand in the expansion chamber, which expansion causes the conversion of pressure energy into velocity energy and the expanding gases rotate at high velocity within the expansion chamber. A partial vacuum is thereby formed in the central portion of the expansion chamber, the partial vacuum occurring after the supersonic wave has passed. As the exhaust stroke of the engine is completed during the formation of this partial vacuum, the weight of exhaust gases remaining in the cylinder from one cycle to the next is materially decreased. While the pressure waves, which cause the objectionable noises, will spread to the walls of the expansion chamber, only a small portion of the pressure waves will escape through the peripheral slot into the peripheral collection chamber. The small percentage of the pressure waves which thus escape from the expansion chamber into the spiral collection chamber will escape at approximately the same time and, therefore, the wave front will not be concentrated in the collection chamber and its exit will be spread over the time required for sound waves to travel the circumferential length of the collection chamber. Also, most of the energy of the pressure waves will be absorbed by the walls of the two chambers as they are reflected from side to side.

While the invention has been illustrated in the form of castings, it will be obvious that the same may be formed of sheet metal or the like and the various elements riveted or otherwise secured together. Also, the whirling motion may be imparted by other means than diffuser vanes. Sufficient whirl can be imparted to the gas in planes parallel to the inlet axis by placing a tall cone in the path of the incoming gas, which gently turns the gas from its linear flow path without reflecting an appreciable pressure rise to the inlet pipe.

I claim:

1. A silencer comprising a hollow substantially toroidal expansion chamber, an inlet therefor, a collection chamber positioned about the outer periphery of said expansion chamber for receiving gases from said expansion chamber, a peripheral slot formed between said chambers to provide communication therebetween, and an outlet for said collection chamber, said collection chamber being formed by a substantially annular inner wall portion and a spiral outer wall portion

whereby said collection chamber gradually increases in cross-section from substantially zero to substantially the cross-sectional area of said outlet.

2. A silencer comprising a hollow substantially toroidal expansion chamber, an inlet therefor, means for imparting whirling motion to the inlet gas in said expansion chamber, a collection chamber positioned about the outer periphery of said expansion chamber for receiving gases from said expansion chamber, a peripheral slot formed between said chambers to provide communication therebetween, and an outlet for said collection chamber, said collection chamber being formed by a substantially annular inner wall portion and a spiral outer wall portion whereby said collection chamber gradually increases in cross-section from substantially zero to substantially the cross-sectional area of said outlet.

3. An exhaust gas muffler for internal combustion engines comprising a hollow substantially toroidal expansion chamber, an exhaust gas inlet conduit connected to said chamber, a substantially annular collection chamber positioned on the outer periphery of said expansion chamber and having a gas outlet, a substantially continuous annular slot formed between said expansion chamber and said collection chamber providing communication therebetween, said slot being less than 360°, and an outlet for said collection chamber, said collection chamber being formed by a substantially annular inner wall portion and a spiral outer wall portion whereby said collection chamber gradually increases in cross-section from substantially zero to substantially the cross-sectional area of said outlet.

4. An exhaust gas muffler for internal combustion engines comprising a hollow substantially toroidal expansion chamber, an exhaust gas inlet conduit connected to said chamber and extending therein, said inlet conduit having diffuser vanes therein to cause the gases to rotate within said chamber, a substantially annular collection chamber positioned on the outer periphery of

said expansion chamber and having a gas outlet, said collection chamber being formed by a substantially annular inner wall portion and a spiral outer wall portion whereby said collection chamber gradually increases in cross-section from substantially zero to substantially the cross-sectional area of said outlet, a substantially continuous annular slot formed between said expansion chamber and said collection chamber providing communication therebetween, said slot being less than 360°.

5. An exhaust gas muffler for internal combustion engines comprising a hollow substantially toroidal expansion chamber, an exhaust gas inlet conduit connected to said chamber, a cone in said expansion chamber for causing the gases to rotate within said chamber, a substantially annular collection chamber positioned on the outer periphery of said expansion chamber and having a gas outlet, said collection chamber being formed by a substantially annular inner wall portion and a spiral outer wall portion whereby said collection chamber gradually increases in cross-section from substantially zero to substantially the cross-sectional area of said outlet, a substantially continuous annular slot formed between said expansion chamber and said collection chamber providing communication therebetween, said slot being less than 360°.
